UNITED STATES PATENT OFFICE.

WILLIAM O. RASTETTER, OF CANTON, OHIO.

POULTRY-FOUNTAIN.

No. 839,422.

Specification of Letters F. tent.

Patented Dec. 25, 1906.

Application filed March 28, 1906. Serial No. 308,430.

To all whom it may concern:

Be it known that I, WILLIAM O. RASTETTER, a citizen of the United States, residing at Canton, in the county of Stark and State of Ohio, have invented certain new and useful Improvements in Poultry-Fountains; and I do hereby declare that the following is a full, clear, and exact description of the same, reference being had to the annexed drawings, making a part of this specification, and to the figures of reference marked thereon, in which—

Figure 1 is a perspective view showing the fountain in position for use. Fig. 2 is a vertical section.

The present invention has relation to poultry-fountains; and it consists in the different parts and combination of parts hereinafter described, and particularly pointed out in the claims.

Similar numerals of reference indicate corresponding parts in both figures of the drawings.

In the accompanying drawings, 1 represents the receptacle proper, which is preferably cylindrical in cross-section and may be of any desired size. The receptacle 1 is preferably formed of clay, properly molded and burned in the usual manner. Near the front or forward portion of the body 1 is located the apertured flange 2, which apertured flange is for the purpose of providing a means for holding the float-rod 3, which float-rod may be connected as shown, or it may be connected in any convenient manner, as its only object is to provide a means for holding and guiding the float 4. Directly in front of the apertured flange 2 is located the flange 5, which flange is spaced a short distance from the apertured flange 2, and is for the purpose of providing a contact-flange for the cement end 6, which cement end is for the purpose of closing the receptacle 1 except at the bottom or lower portion thereof. To the cement end 6 is attached the glass plate or pane 7, which is embedded in the cement while the cement is in a plastic state, said glass pane being for the purpose of producing transparency directly in front of the float 4, so that the amount of water contained in the receptacle 1 can be determined at any time by means of the float 4, said float being located directly behind or back of the glass 7.

For the purpose of assisting in holding the cement end 6 in proper position the body 1 is provided with the groove 8, which groove

is for the purpose of receiving and holding a portion of the cement which is forced in the groove while in a plastic state, and of course after the cement has become hardened the 60 glass and end 6 will be held in proper relative position by the body 1 without danger of displacement.

For the purpose of holding a quantity of water in front of the cement end 6 the cement 65 flange 9 is provided, which cement flange 9 is formed of sufficient height to bring the water-level up to the bottom of the cement end 6, and thereby cut off the flow of water from the receptacle except when air is admitted 70 between the water-level and the bottom of the cement end 6.

It of course will be understood that a supply of water is always maintained for drinking purposes in front of the cement end 6, 75 providing the receptacle contains a sufficient amount of water to bring the water-line above the cement end 6.

In use the receptacle is placed upon its end or brought into a vertical position to be 80 properly filled, after which it is placed in a horizontal position and held against rotation by means of the side flange 10.

For the purpose of convenience in carrying the drinking-fountain the bail 11 is provided, 85 which bail is connected in the ordinary manner.

For the purpose of assisting in holding the flange 9 in proper position after it becomes hardened the body 1 is provided with the 90 groove 11^a, which groove is formed substantially as shown in Fig. 2, and of course allows a portion of the plastic cement to find its way into the groove and become an integral part of the flange 9. By molding the receptacle 1 in proper form and afterward burning the same I am enabled to produce an earthened receptacle well adapted for the purpose designed and at the same time provide a means for closing the open mouth or end of 100 the receptacle for the purpose specified.

It will also be understood that the glass acts to prevent the water from escaping from the receptacle-body except at such times that the water-level is below the bottom or 105 lower end of said glass.

It will be understood that by forming the body 1 of clay it can be formed in the usual manner upon a potter's wheel, and by forming different-sized bodies they can be nested 110 in the usual manner, or in the same manner that crocks are nested and placed in kilns to

be properly burned; but it is well understood that where the end flanges, which are necessary for holding the liquid in the receptacle, and also holding a quantity of liquid in a position to be accessible for drinking purposes, the bodies cannot be conveniently molded upon a potter's wheel, nor can they be nested; but by my improved manner of manufacture and by providing means for connecting the cement end and flange the main portions of the article can be formed and burned in the usual manner, and the cement ends and flanges afterward connected and permitted to harden, thereby greatly reducing the cost of manufacture, both as to the molding and the saving of kiln-room in burning.

Having fully described my invention, what I claim as new, and desire to secure by Letters Patent, is—

1. In a poultry-fountain, the combination of a receptacle provided with a cement contact-flange, a cement end having embedded therein, a transparency, a float-rod connected at its top and bottom ends and a float located thereon, said float and rod located back of the transparency located in the cement end, a flange secured to the forward end of the receptacle and in front of the cement end of said receptacle, and said cement end spaced at its bottom from the wall of the receptacle, substantially as and for the purpose specified.

2. In a poultry-fountain of the class described, a receptacle-body, an end secured to

said body adapted to partially close the receptacle, said end provided with a transparency, a float-rod and a float located thereon, and a liquid-retaining flange located in front of the end carrying the transparency, substantially as and for the purpose specified. 35

3. In a poultry-fountain of the class described, a receptacle provided with a contact-flange near its open end, a cement end secured to said receptacle and spaced at its bottom edge from the inner surface of the receptacle, a liquid-retaining flange secured to said receptacle and the cement end provided with a transparency, substantially as and for the purpose specified. 40

4. In a poultry-fountain of the class described, a receptacle formed of plastic material, and hardened, said receptacle provided with a holding-flange near its open end, and a cement end adapted to close a portion of the open end of the receptacle, a cement retaining-flange located below the cement end and spaced therefrom, said receptacle being provided with grooves for securing said cement end and said cement flange, respectively, thereto, substantially as and for the purpose specified. 45

In testimony that I claim the above I have hereunto subscribed my name in the presence of two witnesses.

WILLIAM O. RASTETTER.
